(57) **CLAIM**

I claim the ornamental design for a luggage lock, as shown and described.

DESCRIPTION

FIG. 1 is a perspective view of a luggage lock showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The break lines on the shackles of the lock also indicate that the shackles may be flexible and deformed.
